UNITED STATES PATENT OFFICE.

GEORGE H. LOBER, OF TOLEDO, OHIO, ASSIGNOR OF ONE-THIRD TO NELSON J. QUINN
AND ONE-THIRD TO F. W. HINDS, JR., BOTH OF TOLEDO, OHIO.

RADIATOR.

1,284,388.

Specification of Letters Patent. Patented Nov. 12, 1918.

Application filed April 16, 1917. Serial No. 162,501.

To all whom it may concern:

Be it known that I, GEORGE H. LOBER, a citizen of the United States, and a resident of Toledo, in the county of Lucas and State of Ohio, have invented a certain new and useful Radiator; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to radiators, and it has for its object to provide an efficient radiator which may be made at a low cost. The invention provides a radiator which is exceedingly simple both in its construction and in its assembling, and yet provides passageways for water and for air, so arranged as to cause the air to pass in intimate contact with the walls of the radiator through which the water current passes to rapidly cool the water. It also provides means for disturbing the air currents and the same means extends the water stream which flows between the walls of the radiator. By my invention I have also provided means which allows for expansion of the water passageways when the radiator freezes and for the contraction of the water passageways when the radiator thaws.

The invention may be contained in many forms of radiator construction. For purposes of illustrating the practicability of my invention I have selected one of such constructions and shall describe it hereinafter. The construction selected is illustrated in the drawings.

Figure 1 of the drawings illustrates a front view of the radiator. Fig. 2 illustrates a side view of one of the sections of the radiator. Fig. 3 illustrates a section of a portion of the radiator taken vertically through the center of the portion of the radiator, and Fig. 4 illustrates a broken view of one of the plates located intermediate the water passageways of the radiator.

1, Fig. 1, is the inclosing shell of the radiator. 2 is the core of the radiator. The core 2 may be connected to water boxes located in the upper and lower part of the radiator in the manner well known in the art

to allow the water to flow from the upper 55 water box through the passageways of the radiator to the lower water box.

The core of the radiator is formed of pairs of walls 3 and 4 between which the water is allowed to pass. The walls are provided 60 with sinuous recesses which register when the radiator plates 3 and 4 are placed in position and thus form passageways 8 in the radiator substantially of circular cross-section. The passageways are disposed at short 65 distances from each other, leaving intermediate flat passageways connecting the sinusoidal passageways. A pair of springs 5 and 6 are located intermediate each pair of walls 3 and 4. The springs 5 and 6 are 70 also substantially sinusoidal and extend vertically along the central portion of the walls 3 and 4. The springs 5 and 6 register at their troughs and at their crests, so that springs on opposite sides of the pairs of 75 walls 3 and 4 aline to press the walls between the crests. Likewise the troughs of the springs operate to press against each other, so that at intermediate points along the springs they press against the walls 3 or 80 4 and against each other and operate to yieldingly press the walls 3 and 4 to keep them together. A pair of plates 7 may be located intermediate each pair of springs 5 and 6. Each spring will thus be placed in a 85 compartment located intermediate the plates 7 and one or the other of the walls 3 or 4.

The edges of the pairs of walls 3 and 4 may be corrugated so as to form angular corrugations 9 or circular corrugations. In 90 the form of the invention shown the edges of the walls 3 and 4 are provided with angular corrugations. When the walls 3 and 4 are placed together in pairs their edges are soldered so as to seal the water passage- 95 way which is formed between each pair of walls 3 and 4. Each pair of walls may be placed side by side so as to form the usual honeycomb appearance found in radiators, in the manner well known in the art. If 100 plates 7 are used and placed between the pairs of walls their edges are likewise corrugated and the corrugations 10 of the plates 7 are so placed with respect to the corrugations of the adjoining pairs of walls as to 105 produce the honeycomb appearance.

In assembling, the plates and walls may be formed and clamped in a form and the

edges of the walls and plates may be dipped in solder and thus the parts may be securely held in position.

The water passes down between the walls 5 3 and 4 and in the passageways 8. A larger portion of the water passes through the passageways on account of the larger cross area of the passageways. The sinuous form of the passageways carries the water a 10 longer distance by the air currents than if the passageways were straight through the radiator. The air enters the honeycombed radiator front and strikes the ridges formed in the walls 3 and 4 and thus cools the water 15 by the impinging action of the air on the corrugated ridges formed in the walls 3 and 4. When the radiator freezes the walls 3 and 4 will expand against a yielding pressure of the springs 5 and 6. When, however, 20 the water thaws out, the springs 5 and 6 force the walls 3 and 4 together and thus reduce the area of the passageway for the water between the walls 3 and 4.

In the preferred form the springs 5 and 25 6 are placed on the plate 7 and the troughs of the springs are soldered to the plates 7. The troughs are preferably placed so as to abut opposing points located on opposite sides of the plate, so that when the plates are 30 placed in position the springs act in opposite directions to press the walls of the water passageways together, the crests of the springs also being placed in alinement press opposing points of the pairs of walls toward 35 each other.

The invention may be modified by those skilled in the art without departing from the spirit thereof.

I claim:

40 1. In a radiator, the combination of a plurality of pairs of walls forming water pas-

sageways, springs located intermediate the pairs of walls and along the vertical central lines of the walls for yieldingly pressing the walls of each pair together.

45

2. In a radiator, the combination of a plurality of pairs of walls, a pair of springs located between each of the pairs of walls for yieldingly pressing the pairs of adjoining walls together.

50

3. In a radiator, the combination of a plurality of pairs of walls forming water passageways, plates located intermediate the pairs of walls and having secured thereto springs, the said plates being located intermediate the pairs of walls, the springs operating to press the walls together.

55

4. In a radiator, the combination of a plurality of pairs of walls forming water passageways, a plurality of plates located between the pairs of walls, the plates having springs located on opposite sides of the plates, the parts of the springs on each plate registering and secured to the plates at the troughs, the crests of the springs 65 operating to press adjoining walls.

60

5. In a radiator, a plurality of pairs of walls forming sinuous passageways extending the length of the walls, the edges of the walls of each pair being secured together, 70 a plurality of plates located between the pairs of walls, springs located on opposite sides of the plates operating to press adjoining pairs of walls together.

75

6. In a radiator, a plurality of pairs of walls, sinuous springs located between the pairs of walls for pressing the walls of each pair together.

In testimony whereof I have hereunto signed my name to this specification.

GEORGE H. LOBER.

Correction in Letters Patent No. 1,284,388.

It is hereby certified that the name of the second-mentioned assignee in Letters Patent No. 1,284,388, granted November 12, 1918, upon the application of George H. Lober, of Toledo, Ohio, for an improvement in "Radiators," was erroneously written and printed as F. W. Hinds, Jr., whereas said name should have been written and printed as *F. W. Himes, Jr.*, as shown by the records of assignments of this office; and that the said Letters Patent should be read with this correction therein that the same may conform to the record of the case in the Patent Office.

Signed and sealed this 28th day of January, A. D., 1919.

[SEAL.]

R. F. WHITEHEAD,
Acting Commissioner of Patents.

Cl. 257—125.
